UNITED STATES PATENT OFFICE.

ADAH CURRIE LINDHEIMER, OF NEW ROCHELLE, NEW YORK.

CLOTHES-LINE SUPPORT.

1,115,555.

Specification of Letters Patent.

Patented Nov. 3, 1914.

Application filed November 21, 1912. Serial No. 732,757.

To all whom it may concern:

Be it known that I, ADAH CURRIE LINDHEIMER, a citizen of the United States, residing at New Rochelle, in the county of Westchester and State of New York, have invented certain new and useful Improvements in Clothes-Line Supports, of which the following is a specification.

My invention relates to new and useful improvements in clothes line supports, and more particularly to a support for lines which extend over pulleys from a window to an adjacent support, and the primary object of the invention is to provide means whereby lines may be conveniently manipulated from within a structure to prevent endangering lives of the operators.

A further object of my invention resides in providing a device which, while operable from within a structure, will permit the sashes of window to be closed after the clothes are placed on the line.

Another object resides in providing a device which may be readily and quickly set up for operation or taken down when desired, and a still further object resides in providing a device which is extremely simple and durable in construction, inexpensive to manufacture and one which will be very efficient and useful in operation.

With these and other objects in view, my invention consists in the novel features of construction, combination and arrangement of parts as will be hereinafter referred to and more particularly pointed out in the specification and claims.

In the accompanying drawings, forming a part of this application: Figure 1 is a perspective view, showing my device applied to use. Fig. 2 is an enlarged perspective view of the coupling between the arms of the tripod. Fig. 3 is a similar view of the coupling in another position. Fig. 4 is a vertical section through a window casing, showing the manner of securing the clothes line after the same has been filled. Fig. 5 is a perspective view of the clamp removed, and Fig. 6 is an enlarged section as seen on line 6—6, Fig. 4.

In describing the invention I shall refer to the drawings, in which similar reference characters designate corresponding parts throughout the several views and in which 1 indicates the wall of a structure having a window casing 2 formed therein and dis-

posed considerable distance above the surface of the ground (not shown).

Arranged outside the structure and some distance beyond the window is a pole or other support 3 having a supporting hook 4 adjustably clamped thereto, and engaged with said hook is a pulley 5, over which extends an endless clothes line 6. This line is adapted to extend through the window referred to and be operatively supported within the structure, and my invention contemplates an improved support for this purpose. To this end I provide a tripod or frame structure composed of the arms or rods 7, 8 and 9, said arms being connected together by means of the improved coupling 10. This coupling comprises a hollow cylindrical member having a central internally threaded collar 11 formed thereon which receives the upper end of the arm 7 therein and extending longitudinally of the member from opposite sides of the collar 11 are the slots 12. These slots terminate adjacent the ends of member in the transversely extending slots 13, the purpose of which will be hereinafter and more particularly described.

The coupled ends of the arms 8 and 9 are provided with ferrules 14, each of which has a shank or the like 15 extending therefrom and formed on the outer end of the shank is a spherical head 16 adapted to be received within the hollow cylindrical member 10. The heads are introduced through the bore of the collar 11 and are worked toward the ends of the member by moving the shanks 15 through the slots 12 and 13, as shown in Figs. 2 and 3 of the drawings, and when so disposed a substantially universal joint is provided between the arms.

The opposite or free ends of the arms 8 and 9 have the eyes 17 mounted thereon and adapted for engagement with the hooks 18 which are mounted on the inner faces of the window casing 2. These hooks are disposed about midway of the casing and the lower end of the arm 7 has mounted thereon the shank or projection 19 which is adapted to be received in the eye 20 mounted on the foot board 21. This latter eye is preferably disposed in a plane adjacent the left side of casing to allow one to readily work from the opposite side.

Adjustably mounted on the arm 7 adjacent the upper end is the clamp 22 which has

the hook 23 formed thereon, and engaged with this hook is an additional pulley 24. The clothes line 6 also extends over this pulley and it will thus be seen that 5 clothes may be placed thereon and drawn beyond the window to dry. I have also provided means whereby the inner support for the line may be taken down and the window closed after the clothes on the line have 10 been drawn beyond the structure and to this end I provide an improved clamp 25. This clamp comprises a plate 26 which is adapted to be secured to the outer face of the structure immediately adjacent the window casing and has a block or the like 27 formed on the front face thereof. Hingedly engaged with the lower side edge of the block is a plate 28 which cooperates with the one side face of said block, thereby forming jaws for the device. The inner face of the plate 28 and the coöperating side face of block are each provided with a pair of horizontal grooves or channels 29 which are adapted to receive the upper 15 and lower reaches of line 6 therein when the device is clamped over the line, and a handle member 30 is formed on the plate 28 to readily operate the same. In order to lock the clamp in effective position, a bent locking spring 31 is secured on the handle 30 and adapted to engage the lug 32 on the upper side edge of the block 27. Through this medium the clamp may be readily and quickly secured in effective position and in- 20 effectively disposed when desired.

In applying the device to use the pulley 5 is first engaged with a pole or support of any desired type and the line extended through a window of a structure, it being understood 25 that this device is particularly adapted for use in connection with apartments, tenements and the like. The tripod frame structure is then set up so that the arms 8 and 9 are engaged with the hooks 18 on the sides 30 of the window casing and the arm 7 engaged with the eye 20 on the footboard. The clamp 22 is then adjusted on the arm 7 to be disposed in substantially the same horizontal plane as the pulley 5, whereupon the pulley 35 24 is engaged with the hook 23. The device is then ready for use and the arm 7 is so arranged to the left side of the window as to allow the washerwoman to step to the window and readily hang clothes upon the line 40 without leaning her body beyond the window. After the clothes are properly stretched beyond the structure, should it be desired to close the window, the plate 28 of the clamp may be swung up against the 45 block 27 and the reaches of the line 6 clamped therebetween in the grooves 29. This will retain the line taut from the structure to its outer end and the tripod may 50

then be taken down and folded, while the inner pulley 24 and line are released from the support and suspended from the clamp outside the window. When it is desired to remove the garments from the line, the tripod support may, of course, again be set up.

From the foregoing it will be seen that 70 I have provided an improved clothes line support adapted for use in connection with apartments, tenements and the like wherein clothes must be stretched from a window, and it will further be seen 75 that the device is one which will obviate the necessity of a washerwoman endangering her life by leaning from the window. Furthermore, it will be seen that I have provided means whereby the window 80 may be closed after the line is stretched, thereby eliminating the necessity of permitting the air to enter during cold periods of the year.

It will still further be seen that the device 85 is simple and durable in construction, inexpensive to manufacture and one which will be very efficient and useful in operation, and, while I have described the elements best adapted to perform the functions set forth, 90 it is obvious that various changes in form, proportion and the minor details of construction may be resorted to without departing from the spirit or sacrificing any of the 95 principles of the invention.

Having thus described my invention, what I claim is:

1. A collapsible clothes line support including a rod, braces therefor provided at their ends with enlargements, a connecting 100 member therefor provided with a longitudinal slot having terminal lateral offsets, the enlargements being located in the lateral offset portions of the slot and the rod being detachably mounted in the connecting member and closing the central portions of the slot.

2. A collapsible clothes line support including a rod, braces therefor provided at their ends with enlargements, a hollow cylindrical member having a central collar, said cylindrical member having longitudinal slots formed therein on the opposite sides of said collar, the inner ends of said slots communicating with the bore of said collar and the outer ends of said slots having lateral offsets, the enlargements being located in the lateral offset portions of the slots and the rod being detachably mounted in the collar and closing the inner ends of the slots.

In testimony whereof she affixes her signature in presence of two witnesses.

ADAH CURRIE LINDHEIMER.
